FUEL CARTRIDGE FOR CIGARETTE LIGHTERS OR THE LIKE

Charles L. Metzler, Palisades Park, N. J., and Billi Bowen, New York, N. Y., assignors to Stratford Pen Corporation, a corporation of New York

Application July 13, 1950, Serial No. 11,129

Term of patent 14 years

(Cl. D48—27)

To all whom it may concern:

Be it known that Charles L. Metzler and Billi Bowen, both citizens of the United States, residing in Palisades Park, county of Bergen, and State of New Jersey, and city, county, and State of New York, respectively, have invented a new, original, and ornamental Design for a Fuel Cartridge for Cigarette Lighters or the like, of which the following is a specification, reference being had to the accompanying drawing, forming a part thereof, wherein:

Fig. 1 is a top plan view of a fuel cartridge for cigarette lighters or the like, showing my design.

Fig. 2 is a side elevational view thereof;
Fig. 3 is an end elevational view; and
Fig. 4 is an elevational view showing the side opposite Fig. 2.

We claim:

The ornamental design for a fuel cartridge for cigarette lighters or the like, substantially as shown.

CHARLES L. METZLER.
BILLI BOWEN.
